UNITED STATES PATENT OFFICE.

KERVIN R. DUNTON, OF WINCHESTER, MASSACHUSETTS.

DESIGN FOR A CHAIR.

42,932.

Specification for Design.

Patented Aug. 27, 1912.

Application filed April 8, 1911. Serial No. 619,905. Term of patent 7 years.

To all whom it may concern:

Be it known that I, KERVIN R. DUNTON, a citizen of the United States, residing at Winchester, in the county of Middlesex and State of Massachusetts, have invented a new, original, and ornamental Design for Chairs, of which the following is a specification, reference being had to the accompanying drawing, forming a part thereof.

The figure is a perspective view of a chair having a curved back, the upper portion of which comprises a strip extending forwardly and approximately horizontally, and then downwardly, in a continuous curve, the strip being narrowed and abruptly curved at the point where the downward turn is made. The main por-

tion of the strip presents a squared edge, and the downwardly turned portion a chamfered edge. Below the central portion of the strip, and in relief with reference to the front face thereof, is a member presenting a curved but otherwise plain surface, the upper edge being rounded to conform with the curve of the edge of the strip. A vertically arranged strip extends downwardly along the edge of the member in relief.

I claim,

The ornamental design for a chair as shown and described.

KERVIN R. DUNTON.
